UNITED STATES PATENT OFFICE.

JULIUS CRAMER, OF BARMEN, PRUSSIA, GERMANY.

APPARATUS FOR COOLING LIQUIDS IN BOTTLES.

SPECIFICATION forming part of Letters Patent No. 303,815, dated August 19, 1884.

Application filed May 21, 1884. (No model.)

To all whom it may concern:

Be it known that I, JULIUS CRAMER, of Bar-
men, Kingdom of Prussia, German Empire,
have invented an Apparatus for Cooling Liq-
uids in Bottles, of which the following is a speci-
5 fication.

My invention consists in an apparatus for
cooling bottled liquids, comprising a rotative
drum adapted to receive the bottle and the cool-
ing medium and to be tightly closed, and means
10 for turning it into horizontal or vertical posi-
tion, for clamping the bottle in the drum, and
for maintaining a free space within the drum
for the insertion of bottles when ice is used as
15 a cooling medium.

Figure 1 of the annexed three sheets of draw-
ings shows the apparatus in vertical section,
the drum *a* being in vertical position and con-
20 taining a bottle. Fig. 2 is an outside view with
the drum in horizontal position. Fig. 3 is a
portion of the plan corresponding to Fig. 1.
Fig. 4 is a portion of the plan corresponding
25 to Fig. 2, but without drum. Fig. 5 is a vertical
section of a modified arrangement of the
apparatus, and Fig. 6 a part to be used when
small bottles are cooled.

The drum *a* is mounted between rollers *o*,
30 pivoted in a frame consisting of the two rings
b and cross-bars *c*, having journals *k*, by which
the frame is carried in standards *l*, fixed to a
suitable foot. Preferably the drum is provided
35 with two peripheral ribs, *a'*, running in
grooves turned into the rollers. Inside of the
drum there is, according to Fig. 1, at the bot-
tom of the same, a socket, *r*, containing a spiral
40 spring, *d*, and a plate or washer, *e*, to which
are attached springs *f*, adapted to clamp
the bottle from the side, and a basket, *p*, of wire-
work or perforated sheet metal, the purpose
45 of which it is to keep the central portion of the
drum free for the insertion of the bottles when
ice is used as cooling medium. The drum is
provided with a cover, *g*, having a hole in the
middle for the neck of the bottle to pass
50 through, and arranged to be easily removed
and replaced. It may, for instance, be secured
by thumb-nuts on screws hinged to the drum
and engaging with slits in the flange of the
drum and the cover. The edge of the hole in
55 the cover is fitted with a packing-ring, *g'*, adapt-

ed to bear against the shoulder of the bottle,
and a packing is also inserted between the
flanges of the drum and the cover. For the
purpose of keeping the drum in horizontal po-
55 sition when it is to be rotated, the frame *b c* is
provided with a locking device consisting, by
preference, in a springing arm, *m*, Figs. 2 and
4, pivoted to one of the standards *l*, and having
at its outer end a stud arranged to catch at *q*
60 into a hole in the bar *e* when being horizontal.

When a bottled liquid—as, for instance,
champagne—is to be cooled by means of ice, the
frame *b c* is unlocked, whereupon the drum,
whose journals *k* are above its center of grav-
ity, assumes a vertical position. The bottle
65 is then pushed between the springs *f* until it
stands on the plate *e*, the space around the
basket *p* is filled with ice or ice and salt, and
the cover put on and screwed down, the spring
70 *d* serving to prevent the bottle from being
strained by this operation, and also to press it
tightly against the packing *g'*. The frame *b c*
having thereupon been turned into horizontal
75 position and secured therein, as described, the
drum may be rotated by means of the knob *h*,
as may be considered requisite, without con-
siderable disturbance of its contents.

In the modified arrangement shown by Fig.
5 the clamping-springs *f* and the basket *p* are
fixed to the bottom of the drum, while the spring
80 *d* and the washer *e* are contained in a socket,
r', on the inside of the cover *g*, which forms a
cap to be put over and to inclose the top of the
bottle. According to the drawings, this cover
85 is secured by a clamping-screw working in a
bow, *n*, pivoted to the drum, so that it may be
turned down; but the cover may be fastened
by screws such as shown in Fig. 1, or by any
90 other suitable means, and, if it should be pre-
ferred, the cover in the first arrangement may
be held in its place by two bows with clamp-
ing-screws, one on either side of the project-
ing bottle-neck, and alike to the bow *n*.

In case the apparatus, Figs. 1 to 3, is to be used
95 for small bottles, the height between the plate
e and the packing *g'* is reduced according to the
size of the bottles by means of a socket, *s*, Fig.
6, having the bottom *t* and fitting into the socket
r, the spring *d* and the plate *e*, with basket *p*,
100 being transferred to the socket *s*, or other like

parts particularly adapted to the small bottles being used instead thereof. In similar manner the interior height of the apparatus, Fig. 5, may be reduced by a special socket fitting into 5 the socket r' .

I claim as my invention—

1. An apparatus for cooling liquids in bottles, in which are combined a drum, a , mounted rotatively between rollers o , pivoted in a frame, 10 $b\ c$, that can be turned on journals k , a device for locking the said frame when the drum is in horizontal position, and a cover, g , provided with means for securing it to the drum, substantially as and for the purpose described.
- 15 2. The combination, with the drum a , journaled frame $b\ c$, provided with means for locking it, rollers o , and cover g , of a spring, d , adapted to act endwise against the bottle in-

serted into the drum, as and for the purpose specified.

3. The combination, with the drum a , journaled frame $b\ c$, means for locking it, rollers o , cover g , and spring d , of the clamping-springs f , as hereinbefore described.

4. The combination, with the drum a , journaled frame $b\ c$, locking device for the same, rollers o , and cover g , of the basket p , substantially as described, and for the purpose set forth.

In testimony whereof I have signed my name 30 to this specification in the presence of two subscribing witnesses.

JULIUS CRAMER.
